DESIGN FOR A LAMP OR SIMILAR ARTICLE

Harry W. Brooks, Fountain City, Tenn., assignor
to Harry W. Brooks, Knoxville, Tenn., a co-
partnership consisting of Harry W. Brooks and
Leonard Hurley

Application January 2, 1946, Serial No. 125,234

Term of patent 3½ years

(Cl. D48—20)

To all whom it may concern:

Be it known that I, Harry W. Brooks, a citizen of the United States of America, residing at Fountain City, in the county of Knox and State of Tennessee, have invented a new, original, and ornamental Design for a Lamp or Similar Article, of which the following is a specification, reference being had to the accompanying drawing, forming part thereof, in which the figure is a perspective view of a lamp or similar article, showing my new design.

The dominant features of my design reside in the portions shown in full lines.

I claim:

The ornamental design for a lamp or similar article, as shown and described.
